INVENTOR.

WALTER C. MESSEMER
BY

Victor J. Evans
ATTORNEY.

UNITED STATES PATENT OFFICE.

WALTER C. MESSEMER, OF SAN FRANCISCO, CALIFORNIA.

TOY.

Application filed November 26, 1923. Serial No. 677,055.

To all whom it may concern:

Be it known that I, WALTER C. MESSEMER, a citizen of the United States, residing at San Francisco, in the county of San Francisco and State of California, have invented new and useful Improvements in Toys, of which the following is a specification.

This invention relates to improvements in toys and has particular reference to a toy wherein a certain amount of skill is required in order to accomplish the purpose of the toy.

The principal object of this invention is to produce a toy wherein a projectile is caused to move against the tension of rubber springs so as to contact an upright member, causing the same to tip.

Another object is to devise a toy wherein the projectile may be moved about a given path thereby necessitating an accurate aim by the operator.

Another object is to produce a toy which is cheap to manufacture and one which may be confined in a minimum space when not in use.

Other objects and advantages will be apparent during the course of the following description.

In the accompanying drawings forming a part of this specification, and in which like numerals are employed to designate like parts throughout the same,

Figure 1 is a top plan view of my toy, and Figure 2 is a side elevation of Figure 1.

Applicant is aware of the fact that many devices have been created for the purpose of entertainment wherein a plurality of figures were knocked from a vertical position to a horizontal position, but in most of these devices the projectile was free and, consequently, considerable effort was exerted in retrieving the projectile, while in my device I have secured the projectile in such a manner that it is always secured to the toy, but at the same time I have provided means whereby the projectile may be moved throughout a predetermined path thereby allowing an accurate aiming at the object to be hit.

In the accompanying drawings wherein for the purpose of illustration is shown a preferred embodiment of my invention, the numeral 5 designates the support and the numeral 6 a similar support spaced from

the support 5 and mounted parallel thereto.

At 7 and 8, I have shown dowel pins having their ends secured to the support 5 and being slidably engaged by the support 6. Upon the support 5, I place a plate 9 which may be moved to the right or left of the drawing, through the provision of slots 11 and 12 and screws 13 and 14 extending therethrough. This plate is provided with up-turned tongues as shown at 16, 17 and 18, which tongues serve to support target members 19, 21 and 22, respectively. These target members are each provided with a lug as shown at 23, 24 and 26, respectively, which lugs are pivotally secured to the tongues as by bolts or rivets.

Mounted in the support 6 are uprights 27 and 28, which uprights are slotted so as to receive a portion of a rubber band. These bands are designated by the numbers 29 and 31. A cord 32 is connected between the rubber bands 29 and 31 and has slidably positioned thereon a ball 33.

The operation of my device is as follows:—

The device as a whole is set upon the floor or table and the targets 19, 21 and 22 are placed in the full line position of Figure 2, the ball 33 is then moved along the cord 32 until it is in, what the player thinks is, the correct position for striking the target. The ball is then pulled to the dotted line position of Figure 1, with the result that the rubber bands 29 and 31 are stretched thus placing a tension upon the same. When the player releases the ball it travels in the direction of the dotted arrow to its position of rest, thence as indicated by the solid arrow and finally strikes the target 21. If the player moves the ball to a position in front of the targets 19 or 22, the operation will be the same.

Considerable skill is required owing to the uneven stretching of the bands 29 and 31, with the result that a very interesting game, requiring considerable skill, may be enjoyed by the player.

It is to be understood that the form of my invention herewith shown and described, is to be taken as a preferred example of the same, and that various changes in the shape, size and arrangement of parts may be resorted to without departing from the spirit of the invention or the scope of the subjoined claim.

Having thus described my invention, I claim:—

In a toy, parallel spaced supports, adjusting pins extending between said supports, a plate mounted on one of said supports and laterally movable relative thereto, a plurality of targets pivoted to said plate, uprights secured to the other of said supports, resilient members secured to said uprights, a flexible member extending between said resilient members, and a projectile slidable on said flexible member, for the purpose specified.

In testimony whereof I affix my signature.

WALTER C. MESSEMER.
